Primary Examiner — Jennifer L Rempfer(74) *Attorney, Agent, or Firm* — Patricia C. Brzostowicz;
Superior Patent Group, LLC(57) **CLAIM**

The ornamental design for a flat-fold fitted sheet, as shown and described.

DESCRIPTION

FIG. 1 is a perspective view for the flat-fold fitted sheet;
 FIG. 2 is a front view of the flat-fold fitted sheet;
 FIG. 3 is a back view of the flat-fold fitted sheet;
 FIG. 4 shows a left view of the flat-fold fitted sheet;
 FIG. 5 shows a right view of the flat-fold fitted sheet;
 FIG. 6 is a top view of the flat-fold fitted sheet;
 FIG. 7 is a bottom view of the flat-fold fitted sheet;
 FIG. 8 shows a closed environmental perspective view of the flat-fold fitted sheet;
 FIG. 9 shows an exploded environmental view of the flat-fold fitted sheet; and,
 FIG. 10 shows a detailed view of a corner of the flat-fold fitted sheet from FIG. 3.
 The dashed lines shown in FIGS. 1-3, 8, and 10 show stitching on the flat-fold fitted sheet.

1 Claim, 7 Drawing Sheets(56)
